United States Patent Office

Des. 176,720
Patented Jan. 24, 1956

176,720

STEP STOOL

Samuel L. Hudd, Bellwood, Ill., assignor to Hub Plating
Works, Inc., Broadview, Ill., a corporation of Illinois

Application December 21, 1954, Serial No. 33,628

Term of patent 14 years

(Cl. D15—8)

FIG. 2

Fig. 1 is a front perspective view of a step stool showing my new design;

Fig. 2 is a side perspective view thereof; and

Fig. 3 is a side perspective showing the seat of the stool opened to expose the steps.

I claim:

The ornamental design for a step stool, substantially as shown.
